UNITED STATES PATENT OFFICE.

HARRY L. CASSARD, OF BALTIMORE, MARYLAND.

TELEPHONE TOLL-BOX.

SPECIFICATION forming part of Letters Patent No. 425,161, dated April 8, 1890.

Application filed October 19, 1889. Serial No. 327,592. (No model.)

To all whom it may concern:

Be it known that I, HARRY L. CASSARD, of Baltimore city, in the State of Maryland, have invented a new and useful Improvement in 5 Telephone Toll-Boxes, of which the following is a specification.

My invention relates to that class of devices which are designed to be attached to telephone-boxes for the purpose of exacting tolls 10 from persons using the telephone, and which boxes are constructed with a coin slot and chute into which a coin is to be inserted, and which coin serves when inserted to throw the telephone into circuit and render it operative. 15 Heretofore such devices have been so connected with the telephone-boxes as to involve such alteration and adaptation of the telephone-box, circuit-connections, and mechanical appliances within the subscriber's box as 20 to be objectionable to telephone companies on account of such changes.

My invention contemplates no change whatever in any of the inclosed features of the telephone-box, and proceeds by introducing 25 the toll-box and its appliances in the circuit-wire of the receiver, which extends from the telephone-box to the receiver outside of said box, and which can be easily applied or removed without disturbing any of the interior 30 arrangements of the subscriber's box.

My invention consists in the peculiar construction and arrangement of such extraneous circuit-closing devices and the means for connecting the same with and operating it by 35 the suspension-hook for the receiver, as hereinafter fully described.

Figure 1 is a perspective view of my toll-box applied to the telephone-receiver support, the door of the toll-box being removed. Fig. 40 2 is a front view of the toll-box with the door removed from its hinges, showing a modification of the device in its application to the suspension-hook of the receiver. Fig. 3 is a side view of the telephone-box with the connecting devices shown in Fig. 2 applied thereto.

A is the toll-box, which may be made of any desired shape or material, but is preferably formed as a cast-iron rectangular box with a hinged door. In the back of this box is fixed 45 a non-conducting or insulating rubber plate

B, upon which the electrical connections are mounted.

C is a chute which depends from a slot opening through the upper end of the box. Just below the lower end of this chute there is 55 fixed to the insulating-plate an inclined rest a, consisting of a metal plate, to the outer side of which is attached a guard-plate b by means of a binding-post c. Near this rest is arranged the short end of a lever D, extending 60 through the side of the box. This lever is fulcrumed to an insulated plate E, and its inner end is pulled down and its outer end is pulled up by a spiral spring d, a stop e on this plate serving to limit the upward movement 65 of the outer end of the lever.

F is a binding-post mounted upon the rubber plate and insulated from the other connections. Where the lever D projects through the side of the box, there is a slot which permits the vertical play of the lever. 70

H is a lever-arm fulcrumed to the side of the toll-box and resting at right angles across the outer end of the lever D. This arm is provided with a soft-rubber sleeve s at its 75 end, which is arranged to rest just beneath the forked suspension-hook J, upon which the receiver is hung. This suspension-hook has the usual contact-points within the case, and has a gravitating motion when the receiver 80 is hung thereon, which cuts out the receiver and local battery and throws in the call-bell. When the telephone is in this condition of disuse, the suspension-hook forces the arm H down, and with it the lever D, as shown. 85

The operation of the device is as follows: It will be understood that my toll-box is interposed in the length of the twisted duplicate cord leading from the telephone-box to the receiver. The duplicate cord from the 90 telephone-box comes in one side of the box, and one cord x goes to the binding-post P on the lever-plate E and the other cord y goes to the binding-post F below and passes at y' out the other side of the case to one pole of 95 the receiver. The other cord x' from the receiver goes to the binding-post on the coin-rest. Now when the receiver is taken off the the suspension-hook and the outer end of lever D rises, as shown by dotted lines, the 100

lever-arm H also rises in response to the spiral spring d, and the inner end of lever D is thrown down toward the coin-rest. The instrument is now in condition for operation, except that the circuit of the receiver is broken. This is closed by dropping a coin or its equivalent in the slot. This coin, descending the chute, falls upon the inclined rest a, and is prevented from falling outwardly by the guard-plate b, and is prevented from dropping down by the inner end of lever D. This coin in this position establishes connection between the broken ends x and x' of the receiver-cord and brings the receiver into operative condition, so that communication is possible. When the receiver is hung up after use, the descent of the suspension-hook forces down arm H and lever D, and the inner end of the latter in rising releases the coin, dropping it into the box and breaking connection again between the sections x x' of the receiver-circuit.

It may sometimes happen that after a customer has deposited his coin he may not be able to get the use of the line on account of its occupation by another subscriber. In that case the customer reports the fact to the owner of the office or store, and the latter is enabled, after a few minutes' waiting, to give his customer the use of the line by a private shunt circuit and switch without the depositing of any further pay. For this purpose two wires W W' extend, respectively, from the coin-rest and the lever-plate E to a switch S, located at a distance or out of the observation of the customer, and the proprietor by closing this switch at will can close the receiver-circuit independently of the deposit of a coin.

In case it is more convenient or desirable to place the toll-box at a lower position in relation to the telephone-box, connection between the levers D and H may be made by a pitman or connecting-rod G, as shown in Figs. 2 and 3.

The only difference between the construction shown in Fig. 2 and Fig. 1 is, that in Fig. 2 I place the spring d above and on the right-hand side of the fulcrum of lever D, instead of below and on the left-hand side, as in Fig.

1. In Fig. 2 also wire x goes to the coin-rest and x' to lever D, while in Fig. 1 x' goes to the coin-rest and x to the lever D. In both

cases, however, the circuit is made or broken between the wires x and x' by either the coin or switch in precisely the same manner.

55

Having thus described my invention, what I claim as new, and desire to secure by Letters Patent, is—

1. A telephone toll-box having a pair of terminals adapted to be closed by a coin or its equivalent, combined with and interposed in the extraneous portion of the circuit-wire running from the telephone-box to the receiver, the broken ends of which circuit-wire are connected to the coin-closed terminals of the toll-box, as described.

2. The combination, in a telephone toll-box, of a pair of terminals adapted to be closed by a coin or its equivalent, a circuit-wire extending from the telephone-box to the receiver and having a break whose terminals are electrically connected to the coin-closed terminals, and a shunt-circuit also electrically connected to the coin-closed terminals and provided with a switch, substantially as shown and described.

3. In a telephone toll-box, the combination of a coin-chute, an inclined rest-plate for the coin, with a guard-flange on its outer side arranged beneath the coin-chute, an arresting-lever D for the coin, having a spring for holding its inner end down in position to arrest the coin, and the circuit-wire of the receiver, having one end connected to the coin-rest plate and the other to the coin-arresting lever whereby the circuit to the receiver is completed through the coin, substantially as shown and described.

4. The combination, with a telephone toll-box having a broken circuit from the receiver arranged in the same, and a lever D, for closing the circuit by arresting a coin in transit, of a hinged arm H, disposed at right angles to the lever D and immediately above the same and arranged beneath the suspension-hook of the telephone-receiver, to be depressed by the weight of the receiver to hold the coin-arresting lever of the toll-box out of operation, substantially as shown and described.

HARRY L. CASSARD.
